FRANK L. OHLER, OF TOLEDO, OHIO, ASSIGNOR TO THE HAUGHTON ELEVATOR & MACHINE CO., OF TOLEDO, OHIO, A CORPORATION OF OHIO.

ELEVATOR-GATE-CONTROL DEVICE.

1,412,368.

Specification of Letters Patent. Patented Apr. 11, 1922.

Application filed August 22, 1917. Serial No. 187,619.

To all whom it may concern:

Be it known that I, FRANK L. OHLER, of Toledo, Lucas County, Ohio, a citizen of the United States of America, have invented 5 new and useful Elevator-Gate-Control Devices, of which the following is a specification.

This invention relates to the remote control or actuation of traffic closures. 10 This invention has utility when adapted to elevators, especially for the opening and closing of doors or gates of the cars as well as the shaft doors.

Referring to the drawings: 15 Fig. 1 is a fragmentary side elevation of an embodiment of the invention in an elevator;

Fig. 2 is a fragmentary perspective view of the cable diagram of the device of Fig. 1; 20 Fig. 3 is a plan view of the elevator shaft of Fig. 1, with parts broken away;

Fig. 4 of the counterweight controlling cam is a view looking down thereon, with parts broken away;

25 Fig. 5 is a section on the line V—V, Fig. 4, looking in the direction of the arrow, and Fig. 6 is a wiring diagram of the gate controller.

The building or structure may be provided with a plurality of floors 1 as landings between which an elevator car may travel. These floors having openings therethrough may provide the elevator shaft surrounded by the deck 2 for the actuating 30 machinery, as the electric motor driven hoisting machine 3 for effecting travel of the elevator car 4 up and down in the elevator shaft or well.

The open sides of the car 4 are ways which 40 may be closed by the gravity gates 5, 6. From the gate 5, as a control device therefor, operable to effect lifting and lowering of said gate, extending upward therefrom, is the flexible means or cable 7 passing about 45 the guide pulleys 8, 9, in the adjustable brackets 10, thence downward in the elevator shaft or well past the car 4 to form a bight about the pulley 11, with the end remote from the gate 5 connected in its upward reach to the bottom of the car 4. This 50 bight of the line or cable 7 about the pulley 11 permits the counterweight 12 connected to the pulley 11 to act as a normally non-

traveling counterweight for the relatively traveling gate 5.

The gate 6 has its control line or cable as flexible means 13 extend upward about the guide pulleys 14, 15, adjacent the top of the elevator shaft, thence downward therein to form a bight about the counterweight connected pulley 16, with the upward reach of the line 13 therefrom, also connected to the car 4. With the counterweight 12 poised so that in car travel the gates 5, 6, rest on the car 4, there is a running connection of the car gates with the counterweight 12 independently of any travel of the counterweight 12.

For effecting the gate actuation, the counterweight 12 may be of a mass normally to 70 open or lift the connected gate or gates, and thereby the gates are controlled by shifting the counterweight. Accordingly on the car 4 there may be protruding from a housing, a controller handle 17 for the motor 18 on the deck 2 serving to drive the gate machine 19 in either of two directions. Shifting of the controller 17 to the right, say for opening 75 a gate, by lowering the counterweight 12, brings the controller 17 to contact 32 connected by line 33 extending to coil 34, thence

by line 35 to supply line 36 thereby throwing switch 37. Supply line 38 extends direct to field windings 39 of the motor 18. The throwing of the switch 37 connects line 36 by way of line 40 to the windings 39 and supply line 41 by way of line 42 to these windings 39, thereby completing the three phases for operating the motor 18 in one direction. Shifting of the controller 17 in 80 the opposite direction to contact 43 connects supply line 44 from the line 38 to line 45 for energizing coil 46 thereby throwing switch 47, and through mechanical interlock 48 insuring a throwing out of the switch 37. 85 This connects the supply lines for an opposite direction for travel of the motor 18, say for lifting the counterweight 12 and thereby closing the gates. This gate machine 19, stationary as to the elevator shaft, through 90 speed reduction may rotate the shaft 20 having thereon the adjustable wheel cam 21 of single rotation cycle providing a slow speed initiation, quick travel, with a slow down for stopping. The adjustment of the cam 21 is 95 effected as to its pick-up and slow-down

- throw by the position of the terminal rolls in the radial mounting slots of the plate (Fig. 5). This travel rate holds not only in gate opening, but also in gate closing.
- 5 When the car gate or gates are closed, the cam 21 normally carries one wrap of the flexible means or cable 22. To open simultaneously the connected gates, shifting of the controller 17 causes the gate machine 19
- 10 to unwind the wrap of the line or cable 22 about the cam 21, thus allowing the gate mastering counterweight 12 to settle as to the car 4, as the cable 22 extending down the elevator shaft passes about the counterweight
- 15 carried pulley 23 as a bight in its extent down and up the shaft, the remote end being anchored to the deck 2. As the counterweight 12 settles down, as permitted by the lowering of the pulley 23, the pulleys 11, 16,
- 20 also going down lift the gates 5, 6, through the lines 7, 13. There is accordingly effected simultaneous actuation of the gates 5, 6.
- The gate 6 is provided with the guide roller 24 working in the guide way 25. As
- 25 the gate 6 starts upward, this way 25, through the roller 24, thrusts the gate 6 outward away from the car 4, so that the projection 26 carried by the gate 6, in this initial upward travel of the gate 6 in the guide
- 30 way may engage the ledge 27 of the well door or shaft gate 28, thereby in the ascent of the gate 6 also opening the gate 28 and maintaining such gate open. The gate 28 may have the flexible connection or cable 29 ex-
- 35 tending over the guide pulley 30 to the counterweight 31. The gate 28, although connected to the counterweight 31, is normally closed, as the weight of this gate is such as to overcome the counterweight.
- 40 The multiple gate control, as well as for single car gate control, as disclosed herein, is of simple form for installation with minimum of upkeep attention. Weather conditions or use tend to effect the working lengths
- 45 of operating lines or cables, and for niceties in adjustment of doors for opening and closing conditions with absence of slack, automatic provision is made herein by approximating the length of the actuation cable or
- 50 line 22 as equal to the gate line 7 or 13. With each cable of same length and kind and all under the common load of the counterweight 12, there is no slack, and with the machine adjusted on installation to bring
- 55 the gates to the proper closed position, such is maintained even under varying cable lengths, for the variation of one is present in the other for neutralizing the stretch or shrink. Bracket adjustments or rigid sections may be used in working out the common lengths for the actuation cables. The
- 60 running lines as to the master counterweight 12 accordingly permits this counterweight to effect automatic maintenance adjustment,
- 65 but there is the reserve for gate actuation at

any floor or landing always simply available. The gate opening actuation by the counterweight 12 is more of a releasing action by the gate machine 19 than any paying out drive. The load on the gate machine is for 70 gate closing, in the connection up with such gate or number of gates as may be desired.

What is claimed and it is desired to secure by Letters Patent is:

1. A traveling car, a gate carried by the 75 car, a cable connecting the car and gate, a counterweight with which the cable coacts between the car and gate, and controllable means as to which the car may travel for shifting the counterweight thereby controlling gate actuation.

2. A traveling car, a gate carried by the car, a counterweight for the gate, a cable connected to the gate, extending to coact with the counterweight and normally carrying the counterweight to actuate the gate, and means for shifting the counterweight to control the gate.

3. A traveling elevator car, a gate mounted on the car, a counterweight normally actuating the gate, a cable extending between the gate and car and having a bight in which the counterweight is disposed, and means for controlling the counterweight.

4. A traveling elevator car, a gate traveling with the car, and means for actuating the gate including a counterweight, a running cable connected to the gate and coacting with the counterweight, and a counterweight shifting cable.

5. A traveling elevator car, a gate traveling with the car, flexible means extending upward from the gate and then downward to come up to the car including a bight, and a counterweight disposed in said bight.

6. A traveling elevator car, a gate traveling with the car, a guide stationary as to the car, connecting means between the gate and car including flexible means extending about the stationary guide, said flexible means having a downwardly extending bight, a counterweight disposed in said bight, and means for shifting the counterweight thereby to control the gate.

7. A gate, a counterweight therefor, first 115 and second lines having bights in which the counterweight is disposed, the first line, being connected to the gate, and means for adjusting the second line to effect shifting of the counterweight and thereby through the 120 first line operating the gate.

8. A gate, a counterweight therefor, a stationary guide, flexible means extending from the gate upwardly about said guide and provided with a downwardly extending bight 125 in which the counterweight is disposed, and means operable independently of car travel for shifting the counterweight thereby to control the gate.

9. A gate, a normally gate actuating 130

counterweight for the gate, an elevator car having guide means providing a car in which the gate is disposed, and flexible means between the gate and car including a downwardly extending bight in which the counterweight is disposed.

10. A gate, a normally gate actuating counterweight for the gate, an elevator car having guide means providing a way in which the gate is disposed, flexible means between the gate and car including a downwardly extending bight in which the counterweight is disposed, and controllable means for rendering the counterweight ineffective 15 embodying a cam.

11. A traveling elevator car, a gate traveling with the car, a stationary gate machine for actuating the car gate, first flexible means extending from the machine, and second flexible means extending from the gate for coaction with the first flexible means in effecting gate control, said flexible means being of approximately equal length, whereby length variation of one thereof is neutralized 25 by the other in automatically maintaining the gate positions constant.

12. A traveling elevator car, a gate traveling with the car, a gate actuating machine as to which the car is movable, first and second flexible means extending respectively from the machine and gate and of approximately equal length for neutralizing length variations to preclude affecting gate positions, each of said flexible means being provided with a bight, and a counterweight disposed therein.

13. A plurality of gates, an elevator car having guide means providing ways for the gates, flexible means connecting the gates to

the car including a downwardly extending bight for each gate, and a counterweight disposed in the bights.

14. A plurality of gates, a traveling elevator car on which the closed gates may rest, flexible means extending from the gates to the car including a downwardly extending bight, a counterweight disposed in the bight, and means as to which the car is movable for shifting the counterweight for simultaneously controlling the plurality of gates.

15. A gravity elevator gate, and a control device therefor including a normally gate opening counterweight, and a counterweight loaded line running as to the counterweight in car travel and extending from the gate to the car.

16. An elevator shaft, a gate therefor, a counterweight for actuating the gate, a counterweight loaded line running as to said counterweight in car travel and extending from the gate to the car, and means for controlling the counterweight.

17. An elevator shaft, a gate therefor, a counterweight for the gate, an actuating device for the gate including a normally gate operating counterweight, a counterweight loaded line running as to said counterweight in car travel and extending from the gate to the car, and means for controlling the counterweight.

18. A pair of gates, independent counterweights therefor, a controller for one of the counterweights for shifting one gate, and interengaging means from the one gate effecting shifting of the other gate.

In testimony whereof I affix my signature.

FRANK L. OHLER.

Certificate of Correction.

It is hereby certified that in Letters Patent No. 1,412,368, granted April 11, 1922, upon the application of Frank L. Ohler, of Toledo, Ohio, for an improvement in "Elevator-Gate-Control Devices," an error appears in the printed specification requiring correction as follows: Page 3, line 2, claim 9, for the word "car" read *way*; and that the said Letters Patent should be read with this correction therein that the same may conform to the record of the case in the Patent Office.

Signed and sealed this 2d day of May, A. D., 1922.

[SEAL.]

KARL FENNING,
Acting Commissioner of Patents.
